UNITED STATES PATENT OFFICE.

HENRY TRABOLD, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

DOUBLE CONTROL MECHANISM FOR DOORS.

1,192,476.

Specification of Letters Patent. Patented July 25, 1916.

Application filed March 4, 1915. Serial No. 12,032.

To all whom it may concern:

Be it known, that I, HENRY TRABOLD, a citizen of the United States, and a resident of Philadelphia, county of Philadelphia, 5 State of Pennsylvania, have invented certain Improvements in Double Control Mechanism for Doors, of which the following is a specification.

My invention relates to certain improvements in the means for operating doors and, 10 in some instances, the steps of passenger cars of the type used in city and suburban travel, the motorman's station being located at the front of the car and the conductor's station 15 being placed at or near the rear platform.

One object of the invention is to construct the operating mechanism for the doors at the ends of the car so that the same mechanism can be used either by the motorman or 20 by the conductor.

A further object of the invention is to provide means whereby either of the operating means may be disconnected when the other is used.

25 In the accompanying drawings: Figure 1 is a longitudinal sectional elevation through the center of a car platform, looking toward the doors at the side of the car and illustrating the mechanism for operating the doors; Fig. 2 is a sectional elevation on the line *a*—*a*, Fig. 1; Fig. 3 is a sectional plan view on the line *b*—*b*, Fig. 1; Fig. 4 is a detached perspective view illustrating the operating mechanism; Fig. 5 is an enlarged 30 view showing the clutching mechanism for the motorman's operating shaft; Fig. 6 is a sectional view on the line *c*—*c*, Fig. 5; Fig. 7 is a sectional view on the line *d*—*d*, Fig. 5; Fig. 8 is a detached perspective view of one 35 view showing the clutching mechanism for the motorman's operating shaft; Fig. 9 is a sectional view on the line *e*—*e*, Fig. 7; Fig. 10 is a side view of the conductor's operating handle; Fig. 11 is an enlarged side view of a portion of the vertical operating rod; Fig. 40 12 is a sectional view on the line *f*—*f*, Fig. 10; Fig. 13 is a sectional view on the line *g*—*g*, Fig. 11; and Fig. 14 is a view of a 45 modification.

Referring to the drawings, 1 is the body 50 of the car.

2 is the floor of the platform.

3 is the front bulkhead of the platform in which are located the usual mechanisms for operating the car. In the present instance, 55 the motorman's station is at the point *x* at

the forward end of the platform and the conductor's station is at the point *y* on the platform, but, in some cases, the conductor's station may be inside of the car, the mechanism being extended accordingly.

60

4 is the roof, which extends over the platform in the usual manner.

5 and 6 are the doors located at one side of the platform. Each of these doors is a 65 double door and is separated, in the present instance, by a central post 7, although this post may be omitted in some cases. The door 5 is pivoted at 8 and the door 6 is pivoted at 9.

Mounted in hangers 11 secured, in the 70 present instance, to the roof of the car platform is an operating shaft 10. On the shaft is a slotted arm 12 connected to an arm 13 on a sleeve 14 mounted on a rod 15 secured to the plates on the hangers 11. The arm 13 75 has pins which enter the slots in the arm 12, which is bifurcated in the present instance. On the sleeve 14 is a second arm 16 connected by a rod 17 to an arm 18 on the pivot

80

rod 8 to which the door 5 is attached so that when the shaft 10 is turned the motion will be imparted to the rod 8 to open or close the door. On the rod 8 is an arm 19 connected by a rod 20 to an arm 21 on the rod 9 of the door 6. One of these arms projects inward 85 and the other projects outward, as clearly shown in Fig. 3, so that the doors may open or close in unison when the shaft is turned. On the shaft 10 is an arm 22 connected by a vertical rod 23 to an arm 24 under the 90 platform 2 of the car. This arm projects from a sleeve 25 which is mounted on a spindle 26 carried by hangers 27 secured to the under side of the platform, as shown in Fig. 2. On the sleeve 25 is an arm 28 connected by a rod 29 to a lug 30 on the step 31, which 95 is pivoted at 32 to the framework 2^a of the platform 2 and the mechanism is so mounted that when the rod 23 is moved in one direction the doors will be opened and the step will be lowered, but when it is moved in the opposite direction the doors will be closed and the step will be raised. The rod 23 is flattened at 23^a and is preferably tapered, as shown in Fig. 13, to receive the 100 detachable hand hold 33. The hand hold is forked, as shown in Fig. 12, and has a spring clip 34, which enters a recess 35 in the flattened portion 23^a of the rod and locks the hand hold to the rod to enable the operator

105

110

to move the rod longitudinally to open and close the doors. When the conductor moves from one end of the car to the other he detaches this hand hold and places it on the 5 rod at the opposite end of the car.

In order to allow the motorman to operate the door at the front of the car, I provide a shaft 36 which is mounted in a bearing 11^a at one end and the opposite end of 10 this shaft rests in a recess 10^a in the shaft, as clearly shown in Fig. 5. The end of the shaft within the sleeve is beveled, as at 37, to form a member of a clutch while the base of the recess 10^a is beveled at 38 to correspond with the bevel at the end of the shaft 15 and forms the other member of the clutch, so that when the rod 36 is moved longitudinally by the motorman to permit the two beveled surfaces to engage one another then 20 the shaft 10 is turned with the shaft 36 and when the shaft 36 is withdrawn by a longitudinal movement the two shafts are independent. On the outer end of the shaft 36 25 is a rope wheel 39 to which is attached a rope 40 having hand holds 41 within reach of the motorman. A spring catch 42 on the shaft 36 near the clutch end enters an annular recess 43 in the shaft 10, Fig. 5, when the shaft 36 is moved into engagement with 30 the shaft 10 and acts to retain the shaft 36 in position. When the shaft is withdrawn, as in Fig. 5, a catch 44 enters a recess 45 in the bearing 11^a to hold the clutch out of 35 action, as in Fig. 9.

The above described mechanism is located, 40 in the present instance, on the platform at each end of the car and at the forward end the motorman's shaft 36 is clutched to the shaft 10 and the conductor's hand hold 33 is removed from the rod 23. At the rear 45 end of the car the hand hold 33 is in position and the motorman's shaft 36 is withdrawn from engagement with the shaft 10 so that the doors cannot be operated from this point. In some instances, the mechanism is so arranged that the rod 23 is operated by the motorman and the rope wheel 50 by the conductor.

In Fig. 14, I have illustrated a modification 55 of the invention in which the overhead shaft 10^b is continuous. On the shaft is an arm 12^b and another arm 22^b, the latter arm being connected to the rod 23^b, which is in position to be actuated by the conductor, the 60 other arm 12^b being connected to the door operating mechanism. On the outer end of the shaft 10^b is the operating wheel 39^b and this wheel can be clutched to the shaft by a bolt 46 so that when the bolt is withdrawn 65 the shaft cannot be actuated from the motorman's station and when the hand hold is detached the rod 23^b cannot be readily moved to actuate the door mechanism.

I claim:

65 1. The combination of a passenger car

having a door at one side; an overhead operating mechanism including a longitudinal shaft having two operating devices, one at the motorman's station and one at the conductor's station; and clutch mechanism by 70 which the operating device at the motorman's station may be connected to or disconnected from the said longitudinal shaft.

2. The combination in a passenger car, 75 of a door; an overhead shaft connected to the door; a vertical rod connected to the overhead shaft; means for raising and lowering said rod to open and close the door; a wheel at the motorman's station; means for turning the wheel in either direction; and 80 clutch mechanism between the wheel and the overhead shaft so that the wheel can be disconnected from the shaft when necessary.

3. The combination in a passenger car, 85 of a platform; a door at the side of the platform; a shaft; means connecting the shaft with the said door; a second shaft arranged to be coupled to the first mentioned shaft; a 90 rope wheel on said last mentioned shaft; a rope extending from the said wheel in a position to be actuated by the motorman; means for retaining the last mentioned shaft in either of its two positions so that, when it is in engagement with the first mentioned shaft, it can be used to open or close the 95 door.

4. The combination in a passenger car, of 100 a platform; a door at the side of the platform; an overhead operating shaft having an arm connected to the door, said shaft also having a second arm; a rod connected to the latter arm and extending in a position to be actuated by the conductor, one 105 end of said shaft being shaped to form one member of a clutch; a motorman's operating shaft in line with the first mentioned shaft and having one end also shaped to form one face of a clutch and arranged to engage the clutch face of the first mentioned shaft; means for turning the motorman's 110 operating shaft; and means for holding the shaft in either of its two positions.

5. The combination in a passenger car, 115 of a platform; a door at the side of the platform; an overhead operating shaft; an arm 120 thereon; a sleeve having an arm connected to the first mentioned arm and having another arm; a rod connecting the last mentioned arm with the door; a second arm on the shaft; an operating rod attached to 125 the arm and located at the conductor's station, the said shaft having a clutch face at one end; and a motorman's operating shaft in line with the first mentioned shaft and also having a clutch face arranged to 125 engage the clutch face of the first mentioned shaft, said motorman's operating shaft being capable of being moved longitudinally into and out of engagement with the first mentioned shaft.

6. The combination of a passenger car, having a platform; a door at the side of the platform; an overhead operating shaft; bearings therefor, said shaft having an arm; 5 means connecting the arm with the door; a motorman's operating shaft in line with the first mentioned shaft and arranged to be moved longitudinally and to engage and clutch the first mentioned shaft when in one 10 position; and a spring catch arranged to engage the bearing and to hold it in the retracted position.

7. The combination of a passenger car having a platform; a door at the side of the platform; an overhead operating shaft; bearings for the shaft; an arm on the shaft; means connecting the arm with the door; a motorman's operating shaft in line with the first mentioned shaft and arranged to be 15 moved longitudinally and to engage and clutch the first mentioned shaft when in one position; a spring catch arranged to engage the bearing and to hold it in retracted position; and a catch arranged to engage 20 the first mentioned shaft when in its projected position.

8. The combination in a passenger car, of a platform; doors at the side of the platform; means for connecting the doors so 30 that they will operate in unison; an overhead operating shaft having an arm; a sleeve mounted above the shaft and also having an arm connected to the arm of the shaft; means connecting the second arm

with the doors; a second arm on the shaft; 35 a vertical rod attached to the said arm; a detachable handle on the rod; an overhead operating shaft in line with the first mentioned shaft and having a limited longitudinal movement; means for operating the 40 shaft; and a clutch face on each shaft so that when the operating shaft is moved longitudinally in one direction it engages the first mentioned shaft so that when it is turned it will open or close the doors; and 45 means for holding said operating shaft in either of its two positions.

9. The combination in means for operating the doors of passenger cars, of an overhead longitudinal shaft; an arm on said 50 shaft; a vertical rod connected to the arm and extending through the floor of the car, said rod having a wide flattened portion tapered in cross section; a detachable handle having forked ends, the inner walls of the 55 forks being beveled to form a tapered throat and arranged to span the tapered portion of the rod; and a spring lock on the handle arranged to engage the flat portion of the rod. 60

In testimony whereof I have signed my name to this specification in the presence of two subscribing witnesses.

HENRY TRABBOLD.
